[57] CLAIM

The ornamental design for head for an electric cattle prod, as shown and described.

DESCRIPTION

FIG. 1 is a perspective view of a head for a cattle prod showing my new design;

FIG. 2 is a top plan view thereof, the bottom being a mirror image of the top shown;

FIG. 3 is a side elevational view thereof, the opposite side being a mirror image of the side shown;

FIG. 4 is a front elevational view thereof; and

FIG. 5 is a rear elevational view thereof.
